UNITED STATES PATENT OFFICE.

EMERY H. MARSTERS, OF BOSTON, MASSACHUSETTS.

DESIGN FOR A BOTTLE.

41,559.

Specification for Design.

Patented July 11, 1911.

Application filed April 4, 1910. Serial No. 553,449. Term of patent 7 years.

To all whom it may concern:

Be it known that I, EMERY H. MARSTERS, a citizen of the United States, residing at Boston, in the county of Suffolk and State of Massachusetts, have invented a new, original, and ornamental Design for a Bottle, of which the following is a specification, reference being had to the accompanying drawing, forming a part thereof.

The design consists in the body of the bottle substantially square in cross section with rounded corners tapered with the lines diverging upwardly with outstanding bands adjacent the top and the bottom. The sides of the bottle are merged by a rounded shoul-

der at the top into a neck tapering with lines converging upwardly round in cross section provided with a band outstanding adjacent and a little above the shoulder and with an ornamental top at the upper end of the neck formed as a large and small curved ring, the smaller ring disposed upon the larger.

I claim—

The ornamental design for a bottle as shown and described.

EMERY H. MARSTERS.
